UNITED STATES PATENT OFFICE.

LOUIS A. VALDETTARO, OF NEW YORK, N. Y.

VENDING-MACHINE.

1,159,298.

Specification of Letters Patent.

Patented Nov. 2, 1915.

Application filed July 3, 1914. Serial No. 848,745.

To all whom it may concern:

Be it known that I, LOUIS A. VALDETTARO, a citizen of the United States, and a resident of the city of New York, borough of the Bronx, in the county of Bronx and State of New York, have invented a new and Improved Vending-Machine, of which the following is a full, clear, and exact description.

This invention relates to vending machines, and relates more particularly to machines of that type by which, after the dispensing of a certain and fixed number of articles for which coins have been deposited, the next customer will have his coin automatically returned to him in addition to a dispensed article, so that he will receive the latter free of cost.

The invention has for its general objects to improve the construction of apparatus of the character referred to so as to be reliable and efficient in use and absolutely proof against tampering with or improper operation.

More specifically the invention has for its object to provide a simple, effective and novel means whereby the coin, after a certain number have been deposited in the machine and articles received therefor, will be diverted by a valve mechanism into the article delivery chute or way, so that the purchaser will have his coin returned to him in addition to the article he intended to purchase.

A further object of the invention is the provision of an improved plunger mechanism which is normally incapable of operation until a coin is first deposited in the machine, when such mechanism is automatically unlocked by an operating pressure on the plunger, whereby the plunger mechanism is operatively connected with the article-dispensing mechanism and the coin-return mechanism.

Still another object of the invention is the provision of means for preventing re-operation of the plunger mechanism, unless the same has completed its cycle of operation and returned to normal position, there being a ratchet device which permits the plunger mechanism to move on its operating stroke, and after completion of the operating stroke the pawl of the ratchet device is held retracted or in unlocked position so as to permit the plunger mechanism to return to normal position, and at the last part of the return movement the pawl is automatically

released so as to be ready for action on the next operative stroke of the plunger.

The invention has as a further object the employment of a novel coin holder or seat into which the coin is deposited to render the machine operative, such seat having a movable part or keeper which slides laterally or in a plane parallel with the coin during the operation of the plunger mechanism, until the keeper passes out of contact with the coin, when the latter is dislodged from the seat and drops into a suitable receptacle arranged to receive the coins.

With such objects in view, and others which will appear as the description proceeds, the invention comprises various novel features of construction and arrangement of parts which will be set forth with particularity in the following description and claims appended hereto.

In the accompanying drawings, which illustrate one embodiment of the invention and wherein similar characters of reference indicate corresponding parts in all the views, Figure 1 is a vertical section of the machine taken parallel to the plane of the movement of the plunger and dispensing mechanism, the plunger mechanism being shown as having been slightly pushed inwardly so as to release the lock therefor; Fig. 2 is a similar section on an enlarged scale, showing the operating parts in normal position, that is to say, before an operating pressure is applied to the plunger mechanism; Fig. 3 is a section similar to Fig. 2, showing the plunger and dispensing mechanisms in the position they occupy at the end of the operating stroke for dispensing an article; Fig. 4 is a sectional view showing the plunger mechanism near the end of its return stroke and just about in the act of unlocking the article dispensing mechanism, so that it can automatically return to its initial position; Fig. 5 is a horizontal section of the machine, showing the internal mechanism in plan; Fig. 6 is a transverse section on the line 6-6, Fig. 1, drawn on an enlarged scale to illustrate the means for holding a coin in position for rendering the machine operative and the gearing for the article-dispensing mechanism and the coin-return device; Fig. 7 is a similar section showing the coin keeper or abutment at the extreme of its lateral movement after releasing the coin; Fig. 8 is a detail sectional view of the article-dispensing mechanism and showing an article

- as just having been ejected from the magazine or holder; Fig. 9 is a sectional view on the line 9—9, Fig. 8; Fig. 10 is an enlarged sectional view of the coin-return device; 5 Fig. 11 is a detail sectional view on the line 11—11, Fig. 4, showing the plunger mechanism controlling means; Figs. 12 and 13 are detail plan views of the coin holder or seat and its coöperating keeper, showing the 10 latter in normal position in the first figure and in shifted position in the second figure, to permit of the ejection of the coin; Fig. 14 is a sectional view on the line 14—14, Fig. 12, when a coin is in the seat or holder; 15 Fig. 15 is a detail view showing the manner in which the coin is ejected from the holder or seat. Fig. 16 is a perspective view of the forward end of the coin engaging element of the plunger mechanism; and Fig. 20 17 is a sectional view on line 17—17, Fig. 11.

Referring to the drawing, A designates a casing of any approved design which has a suitably-located magazine or article holder B, a dispensing chute C, an ejecting mechanism D, a plunger mechanism E, a coin receptacle F, a coin return or dispensing mechanism G, a coin-receiving mechanism H, a coin supply chute I, and a plunger-actuated gear carriage J, through which 25 the article and coin-dispensing mechanism are operated, and the coin released from the holder H.

The casing A has a suitably-arranged opening 1 at the bottom of the chute C, so 30 that the purchaser can remove the article ejected from the magazine after the placing of a coin in the machine and the operation of the plunger. The magazine is of any desired construction and in the present instance it is shown as a vertically-disposed tube open at its bottom so that a column of boxes or other articles 2 may be supported in such a manner that the lowermost article 3 may be ejected by ejecting mechanism D and drop into the chute C. A baffle 4 is disposed in the upper part of the chute so that the article will strike the same and be deflected to such a position that it will 35 travel edgewise down the chute C and thereby prevent clogging. The articles 2 are supported on horizontally-disposed members 5 extending inwardly from opposite walls of the casing, and traveling between these members is an ejector 6 in the form of 40 a lever pivoted at 7 at an approximately central point, and one end of the lever is provided with a spring 8 which holds the article-engaging end 9 of the lever in operative position. In Fig. 1 the ejector 6 has 45 its end 9 disposed behind the lowermost article 3, so that when the ejecting mechanism moves to the left from the position shown in Fig. 1 to that shown in Fig. 3, the lowermost article will slide horizontally out of 50 the magazine and enter the chute C. After

the lowermost article has been ejected the articles in the magazine drop and depress the ejector 6, so that the latter in returning to the right will slide under the new lowermost article, as shown in Fig. 4, until the 70 right edge of this article is reached, when the lever will snap upwardly to the position shown in Fig. 1, so as to be ready to eject the next article. The ejector 6 is mounted on a horizontal slide 10 movable in guides 11, Figs. 8 and 9, and on the under side of the slide 10 are rack bars 12 which mesh with pinions 13 on a horizontal transverse shaft 14 journaled in bearings 15. On this shaft is a central pinion 16 which meshes with a horizontal rack bar 17 which is fastened to and forms a part of the gear carriage J, so that when the carriage moves to the left from its normal position, by the customer pressing the plunger mechanism, 75 after a coin has been deposited in the machine, the ejecting mechanism will eject an article. This carriage is slidably supported on horizontal guide bars or rods 18 which carry springs 19 that have their left ends 80 bearing against the wall 20 and the right end bearing against the portions 21 of the carriage, so that when the carriage moves to the left the springs are subjected to compression and react at the proper time to return the carriage to normal position, as well as to return the ejector mechanism D to 85 normal position.

The plunger mechanism comprises a horizontally slidable frame or carrier 22 that 90 has, as shown in Fig. 5, laterally-extending members 23 and 24 provided with apertures 25 through which extend parallel stationary rods 26 and 27, which form supports on which the plunger frame moves. The front 95 end of the plunger frame has a stem 28 which extends outwardly through the front of the casing and carries a knob or pushbutton 29. The plunger frame normally occupies a position to the extreme right, as 100 shown in Fig. 2, and a spring 30 on the supporting rod 26 opposes the movement of the plunger to the left when pressure is applied to the pushbutton 29, and when pressure is 105 removed from the latter the spring in expanding returns the plunger mechanism to normal position. The spring 30 is interposed between a shoulder or stop 31 on the rod 26 and the arm 24 of the plunger frame 110 22. The plunger must be pressed inwardly 115 its full extent before it can return, and for this purpose ratchet teeth 32 are provided in the horizontal flange 33 on the frame 22, and coöperating with these ratchet teeth is a spring-pressed pawl 34 which is slidably 120 mounted in a bearing bracket 35 rigidly supported in the casing. Toward the end of the movement of the plunger the pawl 34 125 engages a cam 36 and is forced outwardly to inoperative position, so that the plunger 130

can readily return without the pawl engaging the ratchet teeth, and when in this inoperative position a spring-pressed catch 37, Fig. 11, engages a shoulder or notch 38 in the pawl 34 and holds the same retracted against the tension of the spring 39, which normally operates to hold the pawl in engagement with the ratchet teeth. A releasing cam 40 is carried by the plunger frame 22 and is so arranged that it will engage the catch 37 when the plunger is near the end of its return stroke and thereby release the catch 37 as shown in Fig. 11, whereby the spring 39 returns the pawl into co-operative relation with the ratchet teeth 32 in order that the pawl will be ready to act when the plunger is again pushed inwardly to discharge the article.

On the inner portion of the plunger frame 22 is a horizontally disposed coin-engaging element or ejector 41 which is horizontally disposed and has a limited sliding movement in bearings 42 and 43, and interposed between the bearing 43 and a collar 44 on the coin ejector 41 is a helical spring 45 which surrounds the ejector. This ejector is disposed in line with the coin-receiving or holding device H and when the plunger mechanism is pressed inwardly the extremity 46 of the element 41 engages the coin and ultimately dislodges it from the holder at about the time an article is ejected from the magazine. When the coin ejector first engages the coin as shown in Figs. 1 and 14, the ejector is arrested, while the plunger frame continues to move. This relative movement of the ejector and frame is utilized to unlock the plunger so that it can make its full stroke. The lock for the plunger comprises a vertically movable member 47 slideable in bearings 48 and 49 on the plunger frame 22. This member or lock bolt 47 is provided at its upper end with a finger 50, Fig. 11, which is adapted to engage a fixed stop 51 on the bracket 35, the under side of which is inclined at 51^a, Fig. 17, to permit the finger 50 to ride under and past the same from the full to the dotted line position, Fig. 17, as the plunger reaches the end of its return stroke.

A spring 52 is arranged on the locking bolt 47 and has one end bearing on a collar 53 and the lower end resting on the bearing 48, whereby the spring urges the bolt upwardly so that the finger 50 will be in line with the stop 51. This is the normal position of the parts, so that the plunger cannot be operated, except for a fraction of an inch, unless a coin is placed in the machine, when the locking bolt will be automatically withdrawn and allow the plunger to move its full stroke. This withdrawing of the bolt is effected by a spring-actuated bolt-throwing rod 54 slideable in bearings 55 and 56, Figs. 2 and 3, on the plunger frame 22.

One end of this rod 54 has a cam 57 located adjacent the locking bolt so as to engage the upper end of the latter and cause the bolt to be depressed for throwing the finger 50 of the locking bolt below the stop 51. The unlocking movement of the rod 54 is effected by a helical spring 58 arranged thereon with one end of the spring engaging the bearing 56 and the other end engaging an abutment 59 carried by the rod 54. This bolt-throwing rod 54 is held in set position by a spring-pressed dog or pawl 60 pivoted on the plunger frame 22 and so arranged as to engage in a notch 51 in the rod 54, and when the pawl is engaged in this notch, as shown in Fig. 2, the spring 58 will be under sufficient tension to cause the rod 54 to move to the left, Fig. 2, when the dog 60 is released, and consequently the bolt 47 will be thrown to unlocked position, so that the plunger can be operated. The releasing of the dog 60 is effected by the coin ejector 41, which has on its end 41^a a dog-engaging member 62 that extends over the dog and under the rod 54, the action being such that, when a coin is placed in the machine and the plunger is operated, the coin ejector 41 will first engage the coin and be arrested thereby, while the plunger frame and the parts carried thereby will continue to move toward the left, Fig. 2, and as the part 62 is relatively stationary with the coin ejector, the dog 60 will be released and allow the bolt-throwing rod 54 to shift from the position shown in Fig. 2 to that shown in Fig. 1, thereby releasing the plunger and permitting it to move its full stroke for dispensing an article from the magazine.

The plunger frame when moving inwardly imparts motion to the gear carriage J, and although this carriage and the plunger are separate, the operating connection is effected by the plunger locking bolt 47. When this bolt is depressed or unlocked its lower end 47^a engages the front end of a horizontally-extending member 63 which extends from the right end of the carriage J, and consequently, as the plunger moves to the left, the carriage travels with it, and in so doing the rack bar 17 turns the pinion 16 and causes the article-ejecting mechanism to operate. During the latter part of the article-ejecting movement of the carriage a detent 64 comes into play, and the hook or catch 65 thereof drops behind the right end of the member 63, as shown in Fig. 3, so that the carriage will be locked in its extreme left position. Before the plunger reaches the end of its stroke to the left the bolt-throwing rod 54 encounters an abutment or stop 66 which arrests the said rod while the plunger frame continues to move, and consequently the locking bolt 47 is moved from engagement with the cam 57 of the rod 54, but by reason of its being pressed against

the end of the member 63 there is sufficient friction existent to keep the locking bolt down, and it is only when pressure is removed from the push button or plunger and the latter starts rearwardly that the locking bolt springs upwardly to the position shown in Fig. 3. When the rod 54 is arrested by the abutment 66 the catch or dog 60 engages in the notch 61 so that the cam 57 will be held out of engagement with the locking bolt 47 as the plunger returns to its normal position. The carriage J remains in its left position until the plunger has almost completed its return or backward stroke, when a detent-releasing member 67 moves under the lower end of the detent 64 and raises its catch 65 out of engagement with the member 63, so that the carriage J will return to the position shown in Fig. 2, by the expansion of the springs 19. The detent 64 is pivoted adjacent one end so that the arm that carries the catch 65 will be heavier than the other arm. To insure positive action the spring 68 is connected with the shorter arm to cause a constant pressure on the catch-carrying arm to urge the latter downwardly.

The coin chute I is of any desired construction and embodies a tube so proportioned as to receive a coin of a given denomination, and adjacent the bottom of the chute is a transverse opening 69 through which a knife 70 carried by the plunger is adapted to pass at the beginning of the operation of the machine, so that if any device instead of a coin is inserted in the machine the knife will either cut or engage such device and prevent the same from functioning as a coin to render the machine operative.

The coin-holding element H comprises a vertically-disposed plate 71 which is located directly under the chute and, as shown in Figs. 6, 7, 12 to 15, this plate has a vertical passage 72 open at its top and bottom and open on its rear side, and the side edges are formed with shoulders 73 which serve to arrest the coin delivered from the chute I provided the coin is of the proper denomination. A smaller coin would pass through the lower end of the passage 72 without rendering the machine operative. The upper edge of the plate 71 has a notch or recess 74 to permit the coin ejector 41 to enter and disengage the coin from the shoulders 73, as shown in Figs. 13 and 15. The open rear side of the coin holder 71 is initially closed by a sliding keeper 75 which is a recessed plate parallel with the plate 71. This keeper 75 is slidable on a pair of bars or equivalent means 76 rigidly supported with respect to the coin-holding plate 71. When the keeper is in the position shown in Figs. 6 and 12 the pressure of the coin ejector 41 holds the coin against the keeper, and during the operation of the plunger mechanism

and the movement of the carriage J, the keeper slides to the position shown in Figs. 7 and 13, thereby freeing a coin and allowing it to be thrown out of the coin passage 72 and thence drop into a hopper K located under the carriage J. This movement of the keeper is produced by a pinion 77 meshing with a rack bar 78 on the bottom of the keeper 75, this pinion being fastened to a shaft 79 suitably supported in the carriage J and being connected by bevel gears 80 with a vertical shaft 81 which is also mounted in the carriage J, and on the lower end of this shaft 81 is a pinion 82 which meshes with a horizontal stationary rack bar 83, so that, as the carriage moves, the coin keeper will reciprocate from the position shown in Fig. 12 to that shown in Fig. 13, and vice versa.

The coin-return or refunding mechanism is located between the coin hopper K and coin receptacle F and it includes a short throat or neck 84, Fig. 10, which forms a vertical passage between the hopper and coin receptacle. In this hopper is mounted a valve 85 which swings from one side of the throat or passage to the other. The normal position of the valve is shown in Fig. 2, and it allows the coins to drop into the receptacle F. When, however, a predetermined number of articles have been dispensed the machine will automatically throw the valve 85 to the position shown in Fig. 10, so that the customer will have his coin returned to him in addition to receiving the article he intends to purchase, for when the valve is in the position shown in Fig. 10, the coin will drop into the chute C and pass downwardly to the bottom, where it can be taken out with the article purchased. This valve swings on a horizontal axis 86 at its bottom and is connected by link means 87 with a lever 88 fulcrumed at 89. The upper end 90 of the lever is arranged in the path of a projection or cam device 91 which is fastened to a gear 92 on the shaft 93. This gear meshes with a smaller gear 94 on the shaft 95, as shown by dotted lines in Fig. 10, such shaft having a larger gear 96 that meshes with a rack bar 97 on the gear carriage J. A ratchet wheel 98 and pawl 99 cause the shaft 95 and gear wheel 96 to move together as a unit in an anti-clockwise direction, but permit the shaft 95 to remain stationary while the gear 96 is moved in a clockwise direction with the return movement of the carriage J. To insure against reverse rotation of the shaft 95 a star-wheel 100 is fastened to the shaft, and co-operating therewith is a spring pawl 101. With this arrangement it is obvious that with every revolution of the cam-carrying wheel 92, the cam 91 will strike the lever 88 and cause the valve or gate 85 to shift from its normal position shown in Fig. 2 to that shown in

Fig. 10. Clogging is prevented by a baffle 84 in the passage 84.

The coins can be removed from the coin receptacle F by a suitably arranged normally locked door 102. A trap may be provided at the bottom of the chute to break the force of the dispensed article, as well as to prevent anything from being introduced into the machine in an attempt to steal articles from the magazine. For this purpose the lower portion of the bottom of the chute is formed into a trap 103 that is hinged at 104 and is connected by a suitable flexible element 105 with the member 63 of the carriage J, such flexible element passing around a guide pulley 106, so that, as the machine is operated, the trap 103 swings upwardly from the position shown in Fig. 1 to that shown in Fig. 3. The article in passing down the chute will land on the upwardly-swung trap or plate 103 and be arrested by a stop 107 which is vertically slidable in a guide 108 on the side of the coin receptacle F, and when the carriage J returns to normal position the swinging element 103 will move downwardly to the position shown in Fig. 1 and thereby allow the article to gently continue its movement to the dispensing opening 1 of the casing.

From the foregoing description taken in connection with the accompanying drawings, the advantages of the construction and method of operation will be readily understood by those skilled in the art to which the invention appertains, and while I have described the apparatus which I now consider to be the best embodiment thereof, I desire to have it understood that the apparatus shown is merely illustrative and that such changes may be made when desired as are within the scope of the appended claims.

Having thus described my invention, I claim as new and desire to secure by Letters Patent:

1. A vending machine comprising a dispensing mechanism, a plunger mechanism for operating the dispensing mechanism and normally having a limited initial movement independent of the latter, a lock for limiting the initial movement of the plunger mechanism and preventing the complete movement unless a coin is deposited, means for holding a deposited coin, said lock being mounted independently of the coin-holding means, and a device movable into engagement with the coin by the initial movement of the plunger mechanism for releasing the lock for permitting the plunger mechanism to be fully operated.

2. A vending machine comprising a dispensing mechanism, a plunger mechanism for operating the dispensing mechanism and normally having a limited initial movement independent of the plunger, a lock for limiting the initial movement of the plunger

mechanism and preventing the complete movement unless a coin is deposited, means for holding a deposited coin, said lock being mounted independently of the coin-holding means, a device movable into engagement with the coin by the initial movement of the plunger mechanism for releasing the lock for permitting the plunger mechanism to be fully operated, and means for preventing the plunger mechanism from returning to initial position before it has been moved the full length of its forward stroke.

3. In a vending machine, a plunger mechanism including a sliding frame, a locking bolt mounted thereon, a fixed stop with which the bolt normally engages, a bolt-throwing element on the frame and normally tending to actuate the bolt, a device for holding the said element out of engagement with the bolt, and a coin-engaged means acting during the initial movement of the slide to release the said device to permit the bolt-throwing element to unlock the bolt.

4. In a vending machine, a plunger mechanism including a sliding frame, a locking bolt mounted thereon, a fixed stop with which the bolt normally engages, a bolt-throwing element on the frame and normally tending to actuate the bolt, a device for holding the said element out of engagement with the bolt, a coin-engaged means acting during the initial movement of the slide to release the said device to permit the bolt-throwing element to unlock the bolt, and a dispensing mechanism arranged to be operatively connected with the plunger mechanism through the said bolt when it has been thrown by the said element.

5. In a vending machine, a plunger including a slide, a dispensing mechanism including an actuator, a lock carried by the slide and adapted when in unlocking position to engage the actuator for transmitting motion thereto from the plunger mechanism, a spring-actuated lock-throwing element mounted on the slide, a dog for holding the said element in set position disengaged from the lock, a yieldingly mounted member on the slide for releasing the said dog, means adapted to hold a coin with which the member engages during the first part of the movement of the slide to cause the said dog to be released and to permit the said element to throw the said lock to unlocking position, and means with which the said element engages during the latter part of the operative movement of the slide for effecting an automatic resetting of the element and permitting the lock to disengage from the actuator of the dispensing mechanism and return to locking position.

6. In a vending machine, a dispensing mechanism, a plunger mechanism including a slide, a fixed stop, a locking bolt mounted

on the slide and normally engageable with the stop to permit only a limited initial movement of the slide, coin-controlled means normally tending to unlock the bolt and 5 adapted to be released and unlock the bolt by the initial movement of the slide after a coin is inserted in the machine, and a member engageable with the inserted coin during the first part of the movement of the 10 slide, causing said means to operate to unlock the bolt to permit the slide to complete its movement.

7. In a vending machine, a plunger mechanism including a slide, a fixed stop, a locking bolt mounted on the slide and normally engageable with the stop to permit only a limited initial movement of the slide, coin-controlled means under spring tension tending normally to unlock the bolt and adapted 15 to be released and unlock the bolt by the initial movement of the slide after a coin is inserted in the machine, a member movably mounted on the slide and movable therewith during the first part of its movement to engage 20 the inserted coin and thereby throw the said means into action for releasing the bolt and permitting the slide to fully operate, and a dispensing mechanism automatically operatively connected with the slide when 25 the bolt is in unlocking position.

8. In a vending machine, a dispensing mechanism, a plunger mechanism including a slide, a fixed stop, a locking bolt mounted on the slide and normally engageable with 30 the stop to permit only a limited initial movement of the slide, coin-controlled means movable into engagement with and actuating the bolt to unlock the same by the initial movement of the slide after a coin is inserted 35 in the machine, a member movably mounted on the slide and movable therewith during the first part of its movement to engage the inserted coin and thereby throw the said means into action for releasing the bolt and 40 permitting the slide to fully operate, and means for preventing return movement of the slide after the bolt has been unlocked, except by moving the slide throughout its full forward stroke.

50 9. In a vending machine, a dispensing mechanism, a plunger mechanism for operating the same and including a reciprocatory frame, a coin holder toward and from which the frame moves, a lock spaced from and 55 mounted independently of the coin holder for normally preventing a movement of the frame sufficient to operate the dispensing mechanism, a device movable on and carried by the said frame and arranged to engage a coin in the said holder during the initial 60 movement of the frame for releasing the lock to permit full movement of the frame, ratchet teeth on the frame, and a pawl arranged to engage the said teeth for preventing return movement of the frame, until 65

after the latter has moved its complete stroke.

10. In a vending machine, a plunger mechanism including a reciprocatory body, a locking bolt carried thereby, a fixed abutment with which the bolt is adapted to engage to permit normally only a limited movement of the said body, a spring actuated means for throwing the bolt to unlocking position when the said body is initially moved, a catch normally holding said means against movement, a device adapted to engage a deposited coin when the said body is initially moved to release the said device, a set of ratchet teeth on the body, a spring-pressed pawl engaging the teeth to prevent return movement of the said body until it has reached the end of its operative stroke, and means for automatically releasing the pawl to permit the return movement of the body and adapted to automatically disengage the pawl to permit the same to re-engage the ratchet teeth after the body has reached the end of its return stroke.

11. In a vending machine, a plunger mechanism including a reciprocatory body adapted to be manually moved on its forward stroke, a spring means for returning the body to initial position, a coin-engaging member mounted on the body, a spring pressing on the member to permit the latter to yield when engaged with the coin, a locking device normally preventing full operative movement of the said body, means carried by the body and tending normally to unlock the said device, and means actuated by the movement of the said member to release the second-mentioned means to cause the locking device to unlock.

12. In a vending machine, the combination of a plunger mechanism, a coin holder into which a coin is deposited and having a movable part adapted to move to release the coin, a plunger locking device, means carried by the plunger and arranged to engage and be released by a coin in the holder for unlocking the said device by the first part of the movement of the plunger mechanism to permit the plunger to operate, a reciprocatory element actuated by the plunger and movable transversely to the movable part of the coin holder, a dispensing mechanism operated by the said element, and means for moving the movable part of the said coin holder by said element to permit the coin to be released simultaneously with the movement of the said element.

13. In a vending machine, the combination of a plunger mechanism, a coin holder into which a coin is deposited and having a movable part adapted to move to release the coin, a plunger locking device, means carried by the plunger and arranged to engage and be released by a coin in the holder for unlocking the said device by the first part of

- the movement of the plunger mechanism to permit the plunger to operate, a reciprocatory element actuated by the plunger and movable transversely to the movable part of the coin holder, a dispensing mechanism operated by the said element, and a gearing for moving the movable part of the said coin holder by said element to permit the coin to be released simultaneously with the movement of the said element.
14. In a vending machine, a plunger, a lock for the plunger, a releasing device on the plunger for releasing the lock, a coin-engaging member movably mounted on the plunger and controlling the releasing device to unlock the said lock during the first part of the movement of the plunger, means for receiving a coin and holding the same in a position to be engaged by the said member, a reciprocatory element actuated by the plunger in one direction, means for moving the element in the opposite direction, and a dispensing mechanism operated by the said element.
15. In a vending machine, the combination of a plunger mechanism, a reciprocatory element normally disengaged from the said mechanism, a coin-controlled lock normally locking the plunger mechanism and when released forming a connector between the mechanism to move together, a dispensing mechanism operated by the said element, a detent engaging the said element after the same has reached the end of its operative stroke, means carried by the plunger mechanism for disengaging the detent when the plunger mechanism has reached the end of its return stroke, and means for returning the said element when the detent is disengaged therefrom.
16. In a vending machine, the combination of a reciprocatory plunger, a reciprocatory element, a coin-controlled device carried by the plunger to normally lock the same and adapted when released to engage the said element to move the latter with the plunger, spring means for returning the plunger and element to normal position, a device for automatically engaging the element when it has reached the end of its operative stroke and arrested thereby while the plunger returns, means on the plunger for disengaging the device to permit said element to return to normal position, and a dispensing mechanism operated by the said element.
17. In a vending machine, the combination of a dispensing mechanism, a coin-controlled operating means therefor, a device for holding a coin in position to control the said operating means, said device comprising a fixed element adapted to receive a coin of a definite denomination, a keeper movable with respect to the said fixed element, means for moving the said movable element to permit a coin to be dislodged from the fixed element, and means carried by the operating means to dislodge the coin when the movable element is moved away from the fixed element.
18. In a vending machine, the combination of a reciprocatory plunger, a carriage operated thereby, a dispensing mechanism operated by the carriage, a coin chute, a reciprocatory coin holding element, a movable keeper associated with the said element to initially hold a coin in a position to permit the plunger to operate, and a gearing whereby movement of the carriage causes movement of the said keeper to a position to permit the coin to dislodge from the holding element.

In testimony whereof I have signed my name to this specification in the presence of two subscribing witnesses.

LOUIS A. VALDETTARO.
